UNITED STATES PATENT OFFICE.

JOHN HENRY BUTCHER, OF RUGBY, AND ARTHUR PRIMROSE YOUNG, OF KENILWORTH, ENGLAND, ASSIGNORS TO GENERAL ELECTRIC COMPANY, A CORPORATION OF NEW YORK.

SOUND-EMITTING DEVICE.

Application filed December 11, 1923. Serial No. 679,974.

To all whom it may concern:

Be it known that we, JOHN HENRY BUTCHER and ARTHUR PRIMROSE YOUNG, subjects of the King of Great Britain, residing, respectively, at Rugby and at Kenilworth, in the county of Warwick, England, have invented certain new and useful Improvements in Sound-Emitting Devices, of which the following is a specification.

10 This invention relates to sound transmitters or emitters, such as telephone receivers or loud speakers, for use in the reception of wireless or line telephony. It relates particularly to the type wherein a moving element, associated with a diaphragm or its equivalent, is set in vibration by means of the fluctuations of flux derived from the magnetic circuit in response to oscillating currents received by the apparatus, although 20 it is not limited to this type.

According to the present invention, a magnetic circuit and actuating coil are associated with a hollow casing or barrel which may be formed like a violin belly and which functions as the diaphragm of the instrument. Preferably the magnetic circuit is arranged within the hollow casing, and the moving element is connected to opposite sides of the casing in a manner to transmit its vibrations to the said casing. The casing may be of any material capable of vibrating at audible frequencies, but a casing constructed of box-wood is preferred.

The invention also consists in arranging 35 a diaphragm on each side of the magnetic circuit in place of the hollow casing aforementioned, said diaphragms being actuated in a manner similar to the way in which the hollow casing is actuated. Various types of 40 magnetic circuit may be employed with the hollow casing or double diaphragms but the preferred constructions are set out diagrammatically in the accompanying drawings.

45 In another construction there is provided a magnetic circuit comprising a number of curved or straight magnets arranged substantially in the form of a broken circle or polygon respectively, pole pieces being arranged on each magnet on one side of the plane in which the magnets lie for carrying the operating coils. A cooperating magnetic disc or diaphragm is provided adjacent to the faces of the pole pieces.

50 Another construction comprises a sub-

stantially C-shaped magnetic circuit having the operating coils arranged upon the limbs thereof. A cooperating magnetic disc or reed is disposed adjacent to the pole faces in such a way that magnetic attraction or repulsion causes it to vibrate substantially as a whole, i. e. in a rigid manner.

The novel features which we believe to be characteristic of our invention are set forth with particularity in the appended claims, 55 the invention itself however will best be understood by reference to the following description taken in connection with the accompanying drawings in which Fig. 1 shows a hollow casing with a magnetic circuit arranged within; Figs. 2 and 3 show alternative magnetic circuits; Fig. 4 shows another construction of magnetic circuit for use with a circular magnetic member; Fig. 5 illustrates a diaphragm and Fig. 6 is an end 70 section thereof, and Fig. 7 shows a construction in which the diaphragm is actuated directly by the magnetic flux.

Referring now to Fig. 1, a frame 11 is provided with brackets 12 carrying clamping bolts 13 arranged to engage with the ends 14 of a barrel-shaped tubular casing 15. The ends 14 may be formed of a rigid material such as aluminum, but the tubular portion 15 is formed of any material which is 80 both resilient and able to vibrate at audible frequencies. The magnetic circuit comprises two structures 17 consisting of soft iron laminations arranged substantially in the form of a rectangular C with their openings facing towards one another. The actuating coils 18 are mounted upon the outside limbs as shown and connected by leads 19 to terminals 21. Within the air gaps in the structures 17 is arranged a movable reed 22 which is permanently magnetized, and angle-shaped rods 23 connect the ends of the reed to opposite sides of the tubular casing 15. The reed 22 is consequently supported 85 through the two connecting rods 23, and no other pivot is therefore necessary, although a pivot may be provided centrally of the reed, said pivot being carried by the structures 17. The structures 17 are held in 90 spaced relation to one another, being mounted upon rigid brackets 24 which are in turn secured to the end discs 14. In order that the reed shall be symmetrically disposed with 95 respect to the poles of the structures 17, the ends of the connecting rods are screw-

100
105
110

- threaded and cooperate with milled nuts 25 provided with screw-threads externally which engage with the threaded bosses 26 upon the tubular casing 15. Consequently 5 rotation of one or both of the nuts 25 will permit the adjustment of the reed until it is centrally disposed with respect to the air gaps. In order to facilitate making this adjustment, a longitudinal window may be 10 provided in one or both of the sides of the tubular member 15, said window being formed of a resilient material, such as mica, and this will add to the resiliency of the casing.
- 15 The electric coils 18 are so wound and connected as to produce similar polarities in the poles of each structure which are on the same side of the reed. Consequently, when an oscillating current flows through 20 the coils it will produce a variable flux, which, owing to the permanent magnetization of the reed, will cause the latter to vibrate, these vibrations being transmitted through the connecting rods 23 to the casing 15. It should be noticed that a passage-way is provided in each structure to take the connecting rods.

Fig. 2 shows a substantially similar construction of magnetic circuit, but one in 30 which each of the structures is permanently magnetized. For instance, the pole pieces 27 may themselves be permanent magnets of a material such as cobalt steel, or the main core 28 may itself be a permanent magnet. 35 In either case the polarity of the magnets is such as to produce similar polarities in the pole pieces adjacent the air-gaps on the same side of the reed. The poles adjacent the air-gaps are marked N. and S. to demonstrate this. The actuating coils 18 are disposed between the structures 17 around the reed 22. In this case the reed may be polarized or unpolarized, and we have shown the connecting rods 23 joining the ends of 40 the reed to two diaphragms 29 arranged one on each side of the apparatus, these diaphragms taking the place of the tubular casing shown in Fig. 1. A transformer for regulating the current to the requisite 45 amount is indicated at 31.

With this arrangement, the diaphragms may be connected up to sound pipes in a manner to ensure an accumulative effect, a sound horn or the like being provided to 55 emit the combined sound. It will be obvious, however, that instead of using the diaphragms 29, this magnetic circuit can be employed in the construction of Fig. 1 instead of the one there shown.

60 Fig. 3 illustrates another construction comprising permanent magnets 32 whose ends are connected by soft iron yokes 33 to central poles 34 extending towards one another to form an air gap. Brackets 35 of any non-magnetic material, such as alumin-

ium, are dovetailed into the yokes and cut away in the center as shown. An unpolarized reed 22 has its ends carried by these brackets 35 and around the reed and towards the ends thereof are wound the actuating coils 18. Although we have shown these coils as being mounted directly upon the reed, they may if preferred be carried by the brackets 35. The polarity of the magnets is such as to produce opposite poles on 70 each side of the air gap and the coils themselves are reversely connected so that an oscillating current in the coils will produce a consequent pole, alternately north and south, at the center of the reed. This will 80 cause the reed to be attracted alternately by the pole pieces 34, the reed being sufficiently resilient to permit of this. Connecting rods 23 are secured at one end to the reed and arranged to pass up longitudinal holes in 85 the pole pieces being connected at their outer ends to the tubular casing 15 or alternately to diaphragms after the manner indicated with reference to Fig. 2.

It will be observed that this construction 90 differs from the constructions in Figs. 1 and 2 for the following reasons: In the constructions of Figs. 1 and 2 an oscillating current in the actuating coils 18 causes the reed to vibrate about its mid point, which in 95 turn causes the upper and lower sides of the casing 15 or the diaphragms 29, as the case may be, to be drawn towards one another at the same time and then repelled from one another. In the construction shown in Fig. 100 3, however, an oscillating current will cause the upper side of the casing to be drawn towards the structure whilst the lower side is being repelled therefrom, and vice versa.

Another form of magnetic circuit is illustrated in Fig. 4 comprising a number of curved bar magnets 36 arranged substantially in the form of a broken circle. On one side of each magnet are fixed pole pieces 37 adapted to carry the actuating coils (not 105 shown in this figure). A cooperating magnetic disc is provided adjacent the faces of the pole pieces, and the actuating coils are so connected as to cause the attraction of the magnetic disc towards and away from the 110 pole pieces. A similar structure may be used cooperating with a magnetic disc carried upon one side of the hollow casing.

A suitable non-magnetic diaphragm for use with apparatus as above described and 115 sound emitters or transmitters in general may be constructed as shown in Figs. 5 and 6 comprising a thin disc of fabric 38 impregnated with a synthetic resin and having annular corrugations of synthetic resin 39 120 mounted on each side of the fabric disc.

Fig. 7 depicts a construction of magnetic circuit wherein the coils 18 are disposed upon laminated pole pieces 41 of a permanent magnet 42. A diaphragm or magnetic 125

member 43 formed of rigid material is mounted so as to have a small air-gap between each face of the pole pieces and the diaphragm itself. The member 43 is ar-

5 ranged so that the pole pieces are adjacent its periphery and is carried by V-shaped clamps 44 formed of impregnated fabric. Owing to the position of the pole pieces relatively to the member 43 oscillating cur-
10 rent in the coils 18 causes the member 43 to vibrate as a whole.

What we claim as new and desire to se-
cure by Letters Patent of the United States,
is,—

15 1. The combination in a sound emitting device of a hollow casing which serves as a diaphragm and an actuating mechanism enclosed in said casing and attached to oppo-
site sides thereof.

20 2. The combination in a sound emitting device of a hollow casing of non-magnetic material which serves as a diaphragm and an actuating mechanism enclosed in said cas-
ing and attached to opposite sides thereof.

25 3. The combination in a sound emitting device of a hollow tubular casing having its ends closed, which serves as a diaphragm and an actuating mechanism enclosed in
30 said casing and attached to opposite sides thereof.

4. The combination in a sound emitting device of a hollow casing which serves as a diaphragm and an actuating mechanism

within said casing, comprising a magnetic structure, actuating windings and a movable 35 armature which is attached to opposite sides of said casing.

5. The combination in a sound emitting device of a hollow tubular casing of non-
magnetic material, having its ends closed, 40 and the sides of which serve as a dia-
phragm, and an actuating mechanism en-
closed in said casing and attached to oppo-
site sides thereof, said actuating mechanism
being supported by the ends of said casing. 45

6. The combination in a sound emitting device of a hollow tubular casing of non-
magnetic material having its ends closed,
and the sides of which serve as a diaphragm,
and an actuating mechanism enclosed in 50
said casing and attached to opposite sides
thereof, said actuating mechanism being
supported by the ends of said casing and
being adapted to simultaneously produce vi-
bration of both sides of the casing. 55

7. A sound emitting device comprising a hollow casing having end portions, actu-
ating mechanism mounted on said end por-
tions, and a movable armature cooperating
with said actuating mechanism and oppo-
site portions of said casing. 60

In witness whereof, we have hereunto set
our hands this nineteenth day of November,
1923.

JOHN HENRY BUTCHER.
ARTHUR PRIMROSE YOUNG.
